UNITED STATES PATENT OFFICE.

MORRIS GERBERG, ALEXANDER HIRSH, AND MITCHEL MORGAN, OF NEW YORK,
N. Y., ASSIGNEES TO ATLAS DOLL & TOY CO., INC., OF BALTIMORE, MARYLAND,
A CORPORATION OF MARYLAND.

AUTOMATON.

1,387,482.

Specification of Letters Patent. Patented Aug. 16, 1921.

Application filed October 14, 1919. Serial No. 330,582.

To all whom it may concern:

Be it known that we, MORRIS GERBERG, a citizen of the United States, residing in the borough of Manhattan, city, county, and State of New York, ALEXANDER HIRSH and MITCHEL MORGAN, both Russian subjects, and residing in the borough of Bronx, city and State of New York, county of Bronx, have invented new and useful Improvements 10 in Automatons, of which the following is a specification.

This invention has as one of its objects the provision of a hollow doll body comprised of relatively thin sheet metal, formed by 15 press methods into shape, together with the upper and lower limbs, which are attached in a novel and practical manner permitting them to turn freely with respect to the body, and also to move limitedly in a lateral direction, allowing the doll to assume positions 20 simulative of the human body.

A further object is to provide a pair of eyes with means for causing a rolling action, simulative of opening or closing, according to the posture of the doll head in 25 which they are removably engaged.

These objects are attained by the novel construction and assembly of parts herein-after described and shown in the accompanying drawings, forming a material part 30 of this disclosure, and in which:—

Figure 1 is a front elevational view of a doll made in accordance with the invention, showing one of the lower limbs attached.

Fig. 2 is a fragmentary side elevational view showing the lower part of the body and limb attaching seat.

Fig. 3 is a fragmentary side view of one 40 of the lower limbs, looking from the inner side, and showing the engaging means.

Fig. 4 is a fragmentary transverse sectional view taken on line 4—4 of Fig. 3.

Figs. 5, 6 and 7 are sectional views each 45 being taken substantially on line 7—7 of Fig. 1, showing the connecting means used between the limb and body in various positions.

Referring to the drawings in detail, the 50 numeral 15 indicates the front portion of the doll body and 16 the rear, the same being joined along their closely fitted side edges by solder or like securing means.

The sides are curved outwardly as usual

except at two points, near the top on opposite sides, where the sheet metal is formed to present flat surfaced annular plates or seats 17 representing the shoulders.

At the lower portion of the body similar but slightly larger seats 18 are provided, at 60 points representing the hips, for the lower limbs, these seats being inclined downwardly and also convergingly inclined toward the front as best shown in Fig. 1.

Central circular openings 19 and 20 are 65 formed through these seats and extending radially from the openings are slits 22, terminating at about one half the distance between the edges of the openings and peripheries of the annular seats, the material 70 on one side of the slits being pressed inward forming angular inclines 24.

The limbs, both arms and legs 26, are also made of metal, in conventional shape and have at their upper ends, on their inner sides, flat annular plates 28 corresponding to the seats 17 and 18.

These plates contain central circular openings 30 in which are engaged the members used in connecting the limbs to the body.

These members are comprised of gromet or washer-like elements 35 disposed on the inner side of the plates, similar elements 36 extending over their outer sides, these elements being integrally connected by sleeves 85 37 passing through the openings 30 and maintaining the parts in proper relation.

The outer elements 36 are slit diagonally at one point from the sleeve outward to their peripheries and the material on one 90 side of the slit is pressed out, forming raised tongues 38 in such manner as to engage the inclines 24, passing below the seats 17 and 18 the operation of assembling being similar to entering a screw into a nut, as clearly 95 illustrated in Figs. 5, 6 and 7, which show successive stages in connecting the parts and holding them in close relation to the plates 28, thereby locking the limbs to the body but permitting them to turn relatively, the 100 sleeves 37 acting as the axis of rotation.

The locking devices, comprised of the washers and their connections, being made of spring material, as thin sheet steel, also permit the limbs to be moved outward from 105 the body to a limited amount, and return them to place when they become free, and it will be clear that the limbs can be freely

rotated on a horizontal plane at any time, the spring effect of the washers being sufficient to maintain them in any adjusted position.

5 Should an injury occur to any of the limbs, it may be replaced in a clearly apparent manner.

Having thus described our invention and set forth the manner of its construction and 10 operation, what we claim as new and desire to secure by Letters Patent, is:—

1. In a doll of the class described, the combination with a hollow metallic body and pairs of upper and lower limbs, of pairs 15 of seats formed on opposite sides of said body, said seats containing central openings, coöoperative seats formed with each of said limbs, spring plate washers secured to the seats of said limbs, said washers being slit 20 tangentially; and means formed in the seats of said body receptive of said washers whereby said limbs are pivotally engaged and prevented from separating.

2. In a doll of the class described, the 25 combination with a hollow metallic body and limbs engageable therewith, of annular seats formed on said body receptive of said limbs, said seats containing central circular openings and single slits extending there-

from, corresponding seats formed at the 30 ends of said limbs, said seats also containing central circular openings, a washer disposed at the back of the limb seats, a second washer engageable through the mentioned slits with the rear of said body seats and a 35 sleeve integral with said washers adapted to rotate in the seat openings and maintain said limbs in engagement with said body.

3. In a toy, in combination, a body portion having member-receiving openings, a 40 slot in the periphery of said openings, a tang adjacent said slot, members having openings adapted to register with the openings in the body portion, a flanged member adapted to be seated in one of said opposing 45 openings and having its flanges extending on the opposite sides thereon, one of the flanges of said members having a slot in its periphery and a tang adjacent said slot and being spaced from the edge of the opening 50 in which it is seated to receive in said space the edge of the opening in the opposing member to hold said member in rotative relation therewith.

MORRIS GERBERG.
